DESIGN FOR A PICKET FENCE

Neal T. MacKenzie, St. Paul, Minn., assignor to
General Timber Service, Inc., St. Paul, Minn.,
a corporation of Delaware

Application June 3, 1942, Serial No. 107,090

Term of patent 14 years

To all whom it may concern:

Be it known that I, Neal T. MacKenzie, a citizen of the United States, residing at St. Paul, in the county of Ramsey and State of Minnesota, have invented a new, original, and ornamental Design for a Picket Fence, of which the following is a specification, reference being had to the accompanying drawing, forming a part thereof.

In the drawing:

Figure 1 is a perspective view of a picket fence with parts in section showing my new design;

Fig. 2 is a front elevational view thereof, portions being broken away for convenience in illustration, and

Fig. 3 is a horizontal sectional view taken on the line 3—3 of Fig. 2.

I claim:

The ornamental design for a picket fence, as shown.

NEAL T. MACKENZIE.
